CN 306223446 * 12/2020*Primary Examiner* — Paula Allen Greene(74) *Attorney, Agent, or Firm* — Cantor Colburn LLP(57) **CLAIM**

The ornamental design for wireless microphone, as shown and described.

DESCRIPTION

FIG. 1 is a rear perspective view of a wireless microphone showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the figures depict portions of the wireless microphone that form no part of the claimed design.
